UNITED STATES PATENT OFFICE

SAMUEL G. CAMPBELL, OF NEWTON, IOWA

SAFETY COCK FOR GAS BURNERS

Application filed June 6, 1928. Serial No. 283,174.

The object of this invention is to provide improved locking means for valves of gas burners and the like to prevent the valves from being accidentally moved to open position.

A further object of the invention is to provide an improved safety lock for the valve of a gas burner which operates not only to prevent movement of the valve from completely closed to open position, but also to prevent movement from certain intermediate points to further opened position, until after the purposeful application of force to release the locking means.

Still another object of the invention is to provide a device of the character set forth which is simple and economical of construction and capable of being attached to a burner valve without a great deal of trouble or expense.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Fig. 1 is an elevation partly in section showing a gas burner having a valve or cock equipped with one form of my improved latching means.

Fig. 2 is a sectional elevation on an enlarged scale on the line 2—2 of Fig. 1.

Fig. 3 is a vertical section through the valve on the line 3—3 of Fig. 2.

Fig. 4 is a bottom plan view partly in section on the line 4—4 of Fig. 2 and illustrating two different positions of the mechanism.

Fig. 5 is a detail horizontal section on the line 5—5 of Fig. 1.

Fig. 6 is a vertical section through a burner valve actuating mechanism and illustrating the application of a different form of my improved safety locking means.

Fig. 7 is a perspective view showing the detached spring latching means employed in the form shown in Fig. 6.

It is a well known fact that in the use of

gas burners such as are commonly employed in heating and cooking stoves and the like, particularly where the burner is equipped with a valve having a lever operating means, as distinguished from a screw threaded operating means, there is considerable danger that the valve will at times be moved to open position inadvertently through contact with clothing of persons moving about the room or by children in their play or acting under the promptings of curiosity. Such acts may at times result fatally to occupants of a room or building or may result in considerable damage to life and property through an explosion which may occur later in the presence of an open flame. It is to prevent such occurrences that I have provided the improved latching means or safety lock which forms the subject matter of this application.

In the accompanying drawings, the numeral 10 is employed to designate a gas burner adapted to be supplied with gas from a feed pipe 12 through a manually operated cock or valve.

The valve here shown includes a valve body 14 having an inlet nipple 16 communicating with the feed pipe 12 and an outlet nipple 18 communicating with the burner 10. The valve also includes a tapered valve plug 20 mounted vertically through the body 14 and having a port 22 extending transversely therethrough and adapted at times to register with the opening through the nipples 16 and 18.

This type of valve also employs an expansive coil spring 24 mounted on the projecting lower end of the valve plug 20 between washers 26, the lowermost of said washers being held in place by a screw 28 threaded in the lower end of the plug 20. It is the function of the spring 24 to apply a yielding pressure on the valve plug 20 to draw it firmly into the tapered bore of the valve body 14.

In this type of valve the valve plug projects upwardly a considerable distance above the body 14 and is provided at its upper end with a laterally extending lever or handle 30 adapted for manual actuation to operate the valve. The valve plug is normally movable through an arc of about 90 degrees and the limits of such movement are defined by a stop

pin 32 projecting laterally from the valve plug 20 and restricted as to movement in either direction by shoulders 34 and 36 formed at the upper end of the valve body 14.

5 The parts hereinbefore described are common and well known and constitute a valve mechanism which is in common use. They are here shown and described in detail to form a basis for the disclosure of my improved safety latching means.

10 In both forms of my invention shown by the accompanying drawing, I employ a yielding latching means adapted for engagement with a ratcheted stop surface on the valve body 14 so that the valve may be locked or latched at any one of several different points between its closed and completely opened positions.

15 In the form shown in Figs. 1 to 5 inclusive, an arcuate ratchet stop 38 is formed on the lower end of the valve body 14. The ratchet stop 38 has its square faces or shoulders turned in that direction toward which the valve moves when approaching closed position.

20 In this form of the invention the valve plug 20 is formed with a longitudinal groove extending throughout that portion of the plug which is inclosed within the valve body 14 and in this groove a latching member 40 is slidably mounted.

25 The latching member 40 projects below the valve body 14 and is formed at its lower end with a laterally projecting latching lug 42, which is adapted to coact with the ratcheted stop 38 by engaging the shoulders thereof.

30 The latching lug 42 is engaged by the uppermost washer 26 and is pressed upwardly into engagement with the ratchet 38 by the action of the coil spring 24.

35 The latching member 40 also projects above the valve body 14 and extends upwardly and terminates in a hood 44 or similar member overlying the upper end of said plug adjacent the valve handle or lever 30.

40 As shown in Fig. 3, the slidable latching member 40 is formed in two parts which meet at a point intermediate of the tapered valve plug 20. This arrangement is merely for convenience of assembly of the parts and to permit insertion of the upper end portion of the latching member from above and the lower end portion from below, since there are projecting parts at the extreme ends of both of said members.

45 In this form of the invention the latching lug 42 is released by thumb pressure on the hood 44 coincident with or just prior to the act of moving the valve or handle 30 toward open position. The pressure moves the slid- 50 able latching member 40 with its latching lug 42 downwardly so that said lug clears the teeth of the ratchet stop 38 and permits free movement of the valve members.

55 When pressure on the hood 44 is released,

the spring 24 acts to return the latching lug 42 to engagement with one or the other of the teeth of the ratchet 38, thus effectively preventing movement of the valve members to further opened position until such time as the latching means is released by purposeful pressure on the member 44.

60 In the form shown in Figs. 6 and 7, an arcuate ratcheted stop 46 is formed on the upper end of the valve body 14.

65 In this form, the latching member itself has the characteristics of a spring. This latching member has its central portion bent to substantially V form as at 48 and this portion underlies and is in close contact with the tapered handle or lever 30, as clearly shown in Fig. 6.

70 At one end, the V-shaped latching member 48 is formed with an upturned anchoring lug or ear 50.

75 In assembling or attaching the latching member to the valve, the lever 30 is removed by taking out the screw 52, which is employed for attaching it to the upper end of the valve plug 20. Then, the latching member is placed in position against the valve plug and the lever and screw are replaced, the screw 52 passing through an aperture 51 in the attaching ear 50.

80 At its opposite end the latching member 48 is formed with a downwardly extending portion 54, which is slidably arranged in a groove 56 formed longitudinally in the upper portion of the valve plug 20.

85 At its lower end, the straight portion 54 of the latching member is formed with a laterally projecting ear 58 adapted to cooperate with the ratcheted stop 46 by engagement with one or another of the teeth or shoulders thereof.

90 To release this form of latching means, upward pressure is applied to the lower member of the V-shaped spring portion 48 at the same time that lateral pressure is applied to move the lever or handle 30 toward open position.

95 It will be noted that in both forms of the mechanism very little extra effort is required to release the latching means and that such effort as is required may be easily and readily applied coincident with the normal act of moving the valve lever.

100 With respect to the first described form, it will be noted that in the natural position of the hand for operating the valve lever, the thumb will overlie the upper end of the valve plug and the only effort required to release the latch is a slight pressure with the thumb downwardly on the hood 44.

105 With respect to the second described form of the invention, it will be noted that the natural position of the hand for moving the valve lever involves a placing of one or more of the fingers beneath the valve lever and in such position that such finger or fingers will

naturally come into contact with the spring portion 48 when it is mounted below said lever. The only extra effort required to release the locking means is an upward pressure against the spring portion 48 with one or more of the fingers, thus causing the straight portion 54 to slide upwardly in the groove 56 and cause the latching lug 58 to clear the ratchet 46.

The particular reason for having several stops for engagement by the latching lug 42 or 58 is to prevent danger which might occur through a closing of the valve followed by an opening movement without relighting the burner. For instance, when children are playing about a room containing a lighted gas burner, they may through curiosity or otherwise, turn the valve to closed or nearly closed position so that the flame will be extinguished and then may thereafter open the valve or attempt to place it in the same condition in which it was originally.

If the burner is not relighted or is not provided with means for automatically relighting it when opened, such an act will of course result in the escape of gas.

When a burner is equipped with my improved latching means for the valve, the valve will be automatically locked in closed or partly closed position, thus preventing the further opening of the valve without a release of the latching means.

By making the stop of ratchet form, there is no interference with closing movement of the valve lever and the latching lug need not be released to permit closing movement.

Although I have shown and described my improved latching means as applied to a valve for gas burners, yet it is obvious that it may also be used for other purposes and particularly for other types and kinds of valves. Hence, I do not desire to be understood as limiting myself to the application of this improvement to valves for gas burners.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. A safety latch for a gas burner valve, said valve including a valve body, a valve plug rotatably mounted therein, and a lever fixed to and projecting laterally from one end of said plug, said safety latch comprising a spring actuated latching member, said valve plug being formed with a longitudinal groove extending to its other end to receive said latching member for sliding movement through the valve body, a stop on said valve body at the end opposite to said lever, and a latching lug carried by the spring actuated

member and arranged to coact with said stop, said latch having a part extending over the end of the valve plug adjacent the lever and adapted to receive thumb pressure for releasing the lug from said stop simultaneously with a turning force applied to said lever for rotating the valve plug.

2. A safety cock comprising a valve body, a tapered plug extending through and projecting at both ends from said body, a handle on one end of said plug, a spring at the opposite end for causing said plug to be firmly seated in the body, and a latch member extending through said body and having one end located adjacent said handle, the other end of said latch member being formed with a laterally directed lug, said body being formed with a ratcheted stop adjacent said spring, said lug being urged by said spring into engagement with said stop.
